UNITED STATES PATENT OFFICE.

EMIL MEYER, OF BUFFALO, NEW YORK.

DESIGN FOR A BAS-RELIEF.

SPECIFICATION forming part of Design No. 13,924, dated May 22, 1883.

Application filed March 31, 1883. Term of patent 3½ years.

To all whom it may concern:

Be it known that I, EMIL MEYER, a citizen of the United States, residing at the city of Buffalo, in the county of Erie and State of New York, have invented and produced a new and original Design for a Bas-Relief, of which the following is a specification, reference being had to the accompanying drawing, forming part thereof.

This design relates to a bas-relief having the form of a medal; and it consists of the representation on the obverse side of the medal

of a building having two towers, A A, flanked by wings B B, and connected by a main portion, C, having a gable, D, as clearly shown 15 in the accompanying drawing.

I claim as my invention—

The herein-described design for a medal, consisting of the representation of a building, as herein shown and described.

EMIL MEYER.
